US00D935454S

(12) **United States Design Patent** (10) **Patent No.:** **US D935,454 S**
(45) **Date of Patent:** **** Nov. 9, 2021**

(54) **STORAGE DEVICE**

(71) Applicant: **Seagate Technology LLC**, Cupertino, CA (US)

(72) Inventors: **Liying Bi**, Foster City, CA (US); **ChuHsun Wu**, Taipei (TW); **Britt C. Ashcraft**, Torrance, CA (US)

(73) Assignee: **SEAGATE TECHNOLOGY LLC**, Fremont, CA (US)

(**) Term: **15 Years**

(21) Appl. No.: **29/713,056**

(22) Filed: **Nov. 13, 2019**

(51) LOC (13) Cl. **14-02**

(52) U.S. Cl.

USPC **D14/348**; D14/365

(57) **CLAIM**

The ornamental design for a storage device, as shown and described.

DESCRIPTION

FIG. 1 is a top perspective view of a first embodiment of a storage device showing our new design;

FIG. 2 is a bottom perspective view thereof;

FIG. 3 is a top view thereof;

FIG. 4 is a bottom view thereof;

FIG. 5 is a right side view thereof;

FIG. 6 is a left side view thereof;

FIG. 7 is a back view thereof;

FIG. 8 is a front view thereof;

FIG. 9 is a top perspective view of a second embodiment of the storage device;

FIG. 10 is a bottom perspective view of FIG. 9;

FIG. 11 is a top view of FIG. 9;

FIG. 12 is a bottom view of FIG. 9;

FIG. 13 is a right side view of FIG. 9;

FIG. 14 is a left side view of FIG. 9;

FIG. 15 back view of FIG. 9;

FIG. 16 is a front view of FIG. 9;

FIG. 17 is a top perspective view of a third embodiment of the storage device;

FIG. 18 is a bottom perspective view of FIG. 17;

FIG. 19 is a top view of FIG. 17;

FIG. 20 is a bottom view of FIG. 17;

FIG. 21 is a right side view of FIG. 17;

FIG. 22 is a left side view of FIG. 17;

FIG. 23 is a back view of FIG. 17;

FIG. 24 is a front view of FIG. 17;

FIG. 25 is a top perspective view of a fourth embodiment of the storage device;

FIG. 26 is a bottom perspective view of FIG. 25;

FIG. 27 is a top view of FIG. 25;

FIG. 28 is a bottom view of FIG. 25;

FIG. 29 is a right side view of FIG. 25;

FIG. 30 is a left side view of FIG. 25;

FIG. 31 is a back view of FIG. 25; and,

(Continued)

FIG. 32 is a front view of FIG. 25.

The broken lines shown in the drawings are included for purposes of illustrating portions of the storage device and form no part of the claimed design. The unshaded surfaces shown between the solid lines and the broken lines form no part of the claimed design.

1 Claim, 24 Drawing Sheets
